UNITED STATES PATENT OFFICE

169,993

AWNNG

William I. Smith, Perrysburg, Ohio, assignor to
The Hettick Manufacturing Company, Toledo,
Ohio, a corporation of Ohio

Application September 30, 1952, Serial No. 21,654

Term of patent 14 years

(Cl. D21—6)

To all whom it may concern:

Be it known that I, William I. Smith, a citizen of the United States and a resident of Perrysburg, Wood County, Ohio, have invented a new, original, and ornamental Design for an Awning, of which the following is a specification, reference being had to the accompanying drawing, forming a part thereof.

In the drawing:

Figure 1 is a front end elevation of the awning, showing my new design;

Figure 2 is a front perspective view of the awning; and

Figure 3 is a side perspective view of the awning.

I claim:

The ornamental design for an awning, as shown:

WILLIAM I. SMITH.
